DETERGENT COMPOSITION
SIMULATING OLIVE OIL SOAPS

Souren Z. Avedikian, New York, N. Y.

No Drawing. Application May 28, 1936,
Serial No. 82,208

12 Claims. (Cl. 87—5)

In the rayon, silk and wool textile and yarn industries, there has always existed a need for a detergent product that would reduce the time of operation of the boiloff and washing without in any way harming or damaging the fabrics and yarns. The desire to develop a substitute for olive oil soap for use in silk and wool de-gumming and boiloffs has occupied technicians for many years without success. Substitutes that have been used or proposed tended to damage or ruin the treated goods, causing loss to the users. The ideal agency would be more rapid in action than those now in use, mild but effective in its result, not damaging the treated fabrics, and relatively less expensive.

There has long existed also a need in the home and for general use of a soap or a cleanser relatively neutral in effect but highly efficient in action, safe for and aiding in the preservation of the beauty of the hands, and at the same time capable of removing unpleasant odors. No such soap or cleanser highly satisfactory in all these respects is now known.

Such a need has also been felt in the field of toilet soaps, shampoos, etc., where highly alkaline conditions are harmful to the user and are to be avoided. It is known that castile soap and some other preparations are good for toilet use. But castile soap and the others are relatively expensive and hence not available to the general public, which as a result resorts to less expensive soaps or soap preparations of detrimentally high alkalinity.

From time to time there have been introduced cleansers and soap powders incorporating some of the materials that I may use in my compositions, but they have been highly alkaline, making them harmful to the skin and injurious to fabrics, such as acetate silks, wools, etc. In my invention certain alkaline substances are combined so as to eliminate harmful alkalinity and assure a product of low pH value, useful for industry and general use since it cleans thoroughly and quickly and at the same time protects the human skin or the fabrics treated. Thus the principal object of my invention is to provide a safe and comparatively inexpensive cleaning agent of low pH value for the textile and related industries and to make a product capable of removing odors and finding application in general usage.

My detergent composition is just as harmless to the goods treated as the olive oil soaps now in general use. Nevertheless, it accomplishes the same degree of cleaning with a smaller concentration and in a shorter period of time. More-

over, it may be made practically independent of the fluctuations in the price of soap as its chief components are stable, chemical commodities and the soap content can be made either zero or so small that its effect on the final price will be 5 relatively negligible.

My composition because of its controlled low pH value and because of its low cost is of great value also for general purposes, especially for the removal of odors in laundering and in washing 10 dishes and cutlery. This mixture is decidedly effective in completely destroying and eliminating fish, perspiration, rancid oil and other offensive odors from fabrics, clothing, porcelain, glassware, cutlery, etc. Owing to the unexpected success 15 with which it has been found possible to control the pH value, use of a composition of this invention in the home for various domestic purposes is innocuous. It can be used for the most delicate fabrics, for housework where it will 20 protect the hands from the usual harm experienced in the use of ordinary cleansers, and for toilet purposes as a shampoo, etc.

Specifically, my detergent composition is the product resulting from the union or mixture of a 25 number of substances which singly do not produce the desired effects but in combination give in action a result superior to that of the soaps and cleansers in industry and in general use. For example, I preferably make use of such abundantly available chemical substances as sodium carbonate or tri-sodium phosphate in combination with di-sodium phosphate, borax and a protecting and adsorbent agent such as bentonite, with or without the further addition of soap 35 and an oxidizing agent such as sodium perborate. I use di-sodium phosphate instead of using tri-sodium phosphate exclusively because I have found that with it I can advantageously control the alkalinity and the pH. It is well 40 known that each of the substances, sodium carbonate or tri-sodium phosphate, di-sodium phosphate and borax, is strongly basic in reaction and exerts a powerful alkaline influence on any substance with which it comes in contact. But 45 I have found that the united effect of the three differs markedly from that of the sodium carbonate or tri-basic phosphate. A solution of di-sodium phosphate and borax acts in a manner approximating a buffer and its alkaline strength 50 is low. The addition of such a strongly basic reagent as soda ash or tri-sodium phosphate to this solution does not bring about a great change in the pH of the solution as it would in a solution of pure water, and the alkaline strength

remains at a relatively low pH, thus eliminating the dangers which go with high alkaline strength. Ordinarily, a small amount of tri-sodium phosphate gives in water a pH greater than 10.8 pH units. In my buffer solution, however, approximately six times that amount of tri-sodium phosphate will give a pH of 9.6 to 10.0.

The adsorbent substance used in conjunction with these alkaline compounds I have found acts as a protective agent, and furthermore assists in removing or adsorbing odors. Bentonite is mentioned as an example only, and any equivalent may be used, such as any other active clay, charcoal, activated carbon, silica gel and other such substances which have the property of adsorbing odors, etc. I may dispense with the adsorbent material under certain conditions.

In addition to the foregoing substances it is sometimes desirable to include soap to act as a supplementary, colloidal cleaning substance. In some cases, I may also add an oxidizing agent, such as sodium perborate.

Sodium pyrophosphate, i. e., tetra-sodium phosphate, may be used in place of di-sodium phosphate to form the buffer mixture with borax.

Some examples may here be cited which embody my invention and which act in the manner described above. The following are specific examples of some mixtures including the buffer mixture of di-sodium phosphate and borax (sodium tetraborate) and the other components of each mixture, together with the quantities of each.

Example I

	Pounds
Sodium carbonate	15
Di-sodium phosphate	25
Sodium tetraborate (borax)	25
Bentonite	35

Example II

	Pounds
Sodium carbonate	15
Di-sodium phosphate	25
Sodium tetraborate (borax)	20
Bentonite	20
Soap	10
Sodium perborate	10

Example III

	Pounds
Tri-sodium phosphate	40
Di-sodium phosphate	20
Sodium tetraborate (borax)	20
Soap	20

Example IV

	Pounds
Tri-sodium phosphate	30
Di-sodium phosphate	15
Sodium tetraborate (borax)	15
Soap	20
Bentonite	20

These are preferably prepared by first pulverizing each of the components and then mixing them in the proper amounts in a dry-powder mixer, which will give intimate, thorough mixing of the substances that go to make up the formula. The uniformly mixed powder so obtained is preferably used as such. If desired, however, a bonding material may be used to form these various powdery substances into cakes. The powder form has the advantage of producing a solution quickly. The solid materials dissolved in water may be put up as liquid preparations.

The concentrations and other data here cited are for the sake of example only and other concentrations, mixtures, etc. may be used; wide variations in the relative percentages of the materials making up the composition are possible so long as the buffer mixture of di-basic sodium phosphate and borax, or tetra-sodium phosphate and borax, is present and so long as the limiting pH of the water solution is at about 10 pH units. All such departures from the figures given and equivalents are intended to be within the scope of this invention.

The salts of the alkali metals equivalent to sodium phosphate, di-, tri- and tetra-basic forms, sodium carbonate, and sodium perborate are included in the category of equivalents of this invention. The mixture of a di-basic or tetra-basic alkali metal phosphate with sodium tetra-borate, assuring low alkalinity, may be used as such with or without the various other materials to provide a predominantly inorganic detergent of a very mild character, but for highly effective action and controlled, relatively low alkalinity the combination therewith of materials such as sodium carbonate and tri-sodium phosphate is to be employed.

I claim:

1. An alkaline detergent composition giving a solution of substantially constant pH comprising a strongly alkaline substance of the group consisting of tri-basic alkali metal phosphates and alkali metal carbonates buffered with a mixture of di-basic alkali metal phosphates and borax in substantially the ratio of 1:1.

2. An alkaline detergent composition giving a solution of substantially constant pH comprising a strongly alkaline substance of the group consisting of tri-sodium phosphate and sodium carbonate buffered with a mixture of di-sodium phosphate and borax in substantially the ratio of 1:1.

3. An alkaline detergent composition giving a solution of substantially constant pH comprising tri-sodium phosphate buffered with a mixture of di-sodium phosphate and borax in substantially the ratio of 1:1.

4. An alkaline detergent composition, of substantially constant pH when in solution, comprising sodium carbonate buffered with a mixture of di-sodium phosphate and borax in substantially the ratio of 1:1.

5. An alkaline detergent composition, of substantially constant pH when in solution, comprising soap and a strong alkaline substance of the group consisting of tri-sodium phosphate and sodium carbonate, said composition buffered with a mixture of di-sodium phosphate and borax in substantially the ratio of 1:1.

6. An alkaline detergent composition, of substantially constant pH when in solution, comprising tri-sodium phosphate and soap buffered with a mixture of di-sodium phosphate and borax in substantially the ratio of 1:1.

7. An alkaline detergent composition, of substantially constant pH when in solution, comprising sodium carbonate and soap buffered with a mixture of di-sodium phosphate and borax in substantially the ratio of 1:1.

8. An alkaline detergent composition, of substantially constant pH when in solution, comprising bentonite and a strong alkaline substance of the group consisting of tri-sodium phosphate and sodium carbonate, said composition buffered with a mixture of di-sodium phosphate and borax in substantially the ratio of 1:1.

9. An alkaline detergent composition, of substantially constant pH when in solution, comprising tri-sodium phosphate and bentonite buffered with a mixture of di-sodium phosphate and 5 borax in substantially the ratio of 1:1.

10. An alkaline detergent composition, of substantially constant pH when in solution, comprising sodium carbonate and bentonite buffered with a mixture of di-sodium phosphate and borax 10 in substantially the ratio of 1:1.

11. An alkaline detergent composition, of substantially constant pH when in solution, com-

prising a strong alkaline substance of the group consisting of tri-sodium phosphate and sodium carbonate, bentonite and soap, said composition buffered with a mixture of di-sodium phosphate and borax in substantially the ratio of 1:1. 5

12. An alkaline detergent composition, of substantially constant pH when in solution, comprising tri-sodium phosphate 40 parts, soap 20 parts, buffered with a mixture of di-sodium phosphate 20 parts, and borax 20 parts.
